UNITED STATES PATENT OFFICE.

SELVIYOR A. SWANSON, OF NORTH TONAWANDA, NEW YORK.

TRACKER MECHANISM FOR PNEUMATIC OR PLAYER PIANOS.

1,242,266.

Specification of Letters Patent.

Patented Oct. 9, 1917.

Application filed September 21, 1916. Serial No. 121,524.

To all whom it may concern:

Be it known that I, SELVIYOR A. SWANSON, a citizen of the United States, and resident of North Tonawanda, in the county of Niagara and State of New York, have invented certain new and useful Improvements in Tracker Mechanism for Pneumatic or Player Pianos, of which the following is a specification.

10 My invention relates to a tracker mechanism for pneumatic or player pianos.

This invention has for one of its objects to provide a mechanism for automatically retaining the music roll in a position whereby its openings are in alinement with the openings in the tracker bar.

Another object of the present invention is to provide a tracker mechanism of the above mentioned character which may be adapted 20 to the music roll holding boxes of different sizes.

An additional object of the invention is to provide a tracker mechanism of the above mentioned character having a new and simple valve arrangement for controlling the same associated therewith.

Still another object of the invention is to provide a tracker mechanism which consists of few parts, is simple in construction 30 and which may be manufactured and placed on the market at a comparatively low cost.

The invention consists in the combinations, arrangement of parts and operations that will be explicitly set forth in detail and 35 illustrated in the accompanying drawings, in which—

Figure 1 is a view showing my tracker mechanism in operative position; and

Fig. 2 is a transverse sectional view 40 through the pneumatic valve.

Like characters of reference indicate like parts in all the views.

The numeral 5 designates a music roll holding box and 6 the cross bar of the piano.

45 The usual tracker bar 7 and the usual winding spool 8 are mounted in the music roll box 5.

The usual spring actuated stub shaft is shown mounted in one side of the box 5 and 50 is designated by the numeral 9. A relatively long longitudinally movable stub shaft 10 extends through an opening in the opposite side of the box 5 and through an opening in a vertical bar 11 which is supported on this side of the box 5. A music roll is shown mounted on these shafts 9 and

10. Mounted between the tracker bar 7 and the music roll is a cylindrical bar 12 having its ends reduced and mounted in bearings or brackets 13 which are preferably secured to the outer face of the vertical sides of the box 5. The reduced ends of this bar 12 are hollow and communicate with ducts or openings 14 which extend to the periphery of the bar 12. These reduced ends are rigidly secured within the bearings or brackets 13 by means of suitable set screws. This bar may be adapted to any size music roll holding box by simply engaging the set screws with the reduced ends 70 of the bar 12 at any point thereon.

The numerals 15 and 16 designate the upper and lower members of the valve chest which are spaced apart by blocks 18. These members 15 and 16 may be secured to the 75 blocks 18 by gluing or the like or by bolts 19, as shown, which extend through these members and through the cross bar 6. The lower member 15 has recesses or pouch chambers 20 formed in its upper face and covering the same are pouches 21. Formed in this member 15 are openings or ducts 22 which communicate with the pouch chambers 20 and which extend to the outer longitudinal edge of said member 15. Communicating 80 with these openings or ducts are tubes 23 which are engaged with the reduced tubular ends of the bar 12. The upper member 16 is formed with a vertically extending member or bellows support 24 having the bellows 85 mounted thereon. This bellows supporting member 24 is provided at its lower end with vertically extending openings 26 which open upon opposite sides of this member 24 and communicate at their lower ends with 90 horizontally extending openings 27 formed in the upper member 16 which in turn communicate with openings 28 that extend at right angles to the openings 27 and establish communication between the same and the atmosphere. Mounted in these openings 28 are valves 29 which normally cut off communication between the atmosphere and the pneumatics 25 and rest on the pouches 21.

105 An exhaust port 30 is located between the members 15 and 16 and communicates with suitable air exhausting means.

Pivotaly supported upon the bar 11 is an arm 31 which contacts with the bearing 10 and is connected with an operating rod 41 110 which in turn is operatively connected with one of the pneumatics 25.

The operation of the tracker mechanism is as follows: Should the music sheet shift to uncover either of the openings 14, atmospheric pressure will force either one of the 5 valves, as the case may be, upwardly which will permit atmospheric pressure to flow into one of the pneumatics 25 to operate the operating rod 41 which in turn actuates the rod 31 to shift the music roll to its original position.

While I have described what is now believed to be the best embodiment of my invention, I wish it understood that the same may be modified in many different respects 15 that may fairly fall within the scope of the appended claim.

What I claim is:

In a means for automatically tracking a music sheet in combination, a music roll 20 holding box, a tracker bar therein, a music roll mounted in the music roll holding box above the tracker bar upon a spring actuated shaft and a longitudinally shiftable shaft, said longitudinally shiftable shaft being 25 relatively long and extending through an opening in the music roll box and through

an opening in a supporting member formed by an upstanding member disposed in a parallel position and at a distance from the music roll holding box and connected thereto by members secured to and disposed at substantially right angles to said supporting member; a projection on the supporting member below the opening for the shiftable shaft, an upstanding member loosely secured thereto and in contact with one end of the longitudinally shiftable shaft at a point intermediate the ends, said upstanding member being loosely connected at its upper end to a bar positioned above and parallel to the music roll holding box, said bar being capable of lateral movement; pneumatics connected to said bar and a hollow ended bar positioned directly above the tracker bar, said hollow ends extending through the 40 music roll box and connected to the pneumatics, the ends communicating with ducts extending to the periphery of the bar, said ducts being normally covered by the music sheet near the edges thereof.

SELVIYOR A. SWANSON.
